(57) **CLAIM**

The ornamental design for the blister pack, as shown and described.

DESCRIPTION

FIG. 1 is an isometric view of a first embodiment of our new blister pack design;

FIG. 2 is a front elevation view thereof shown in FIG. 1;

FIG. 3 is a right side elevation view thereof shown in FIG. 1;

FIG. 4 is a rear elevation view thereof shown in FIG. 1;

FIG. 5 is a left side elevation view thereof shown in FIG. 1;

FIG. 6 is a top plan view thereof shown in FIG. 1;

FIG. 7 is a bottom plan view thereof shown in FIG. 1;

FIG. 8 is a cross-sectional view taken along line 8—8 of FIG. 6;

FIG. 9 is a cross-sectional view taken along line 9—9 of FIG. 2;

FIG. 10 is an isometric view of a second embodiment of our new blister pack design;

FIG. 11 is a front elevation view thereof shown in FIG. 10;

FIG. 12 is a right side elevation view thereof shown in FIG. 10;

FIG. 13 is a rear elevation view thereof shown in FIG. 10;

FIG. 14 is a left side elevation view thereof shown in FIG. 10;

FIG. 15 is a top plan view thereof shown in FIG. 10;

FIG. 16 is a bottom plan view thereof shown in FIG. 10;

FIG. 17 is a cross-sectional view taken along line 17—17 of FIG. 15;

FIG. 18 is a cross-sectional view taken along line 18—18 of FIG. 11;

FIG. 19 is an isometric view of a third embodiment of our new blister pack design;

FIG. 20 is a front elevation view thereof shown in FIG. 19;

FIG. 21 is a right side elevation view thereof shown in FIG. 19;

FIG. 22 is a rear elevation view thereof shown in FIG. 19;

FIG. 23 is a left side elevation view thereof shown in FIG. 19;
FIG. 24 is a top elevation view thereof shown in FIG. 19;
FIG. 25 is a bottom elevation view thereof shown in FIG. 19;

FIG. 26 is a cross-sectional view taken along line 26—26 of
FIG. 24; and,

FIG. 27 is a cross-sectional view taken along line 27—27 of
FIG. 20.

The broken line portion of the figure drawings is included to
show unclaimed subject matter only and forms no part of the
claimed design.
